ABSTRACT: An electrical connector for attachment to a tape cable comprises a four-layer sandwich consisting of a toothed contact to engage one side of the cable, a resilient pad to engage the other side of the cable and a spring to press the contact into the cable, the sandwich being compressed and inserted into a tubular housing which holds it compressed. The housing may then be crimped onto the cable behind the sandwich.

ELECTRICAL CONNECTORS

This invention relates to connectors for making electrical connections with a tape cable and to methods of attaching the connector to the cable.

Tape cables comprise a metallic tape or side-by-side metallic tapes embedded in an insulating material such as a flexible plastics material. Connectors have already been proposed for making electrical connections with the metallic tapes of such cables, the connectors comprising a contact for each individual tape, each contact having at least one tooth arranged to penetrate the insulating material and make contact with the metallic tape. The connectors so far proposed have been somewhat complex and have been so constructed that to connect them to the tape cable a somewhat complex and time-consuming procedure is necessary.

According to the present invention, a method of attaching a tape cable connector to a tape cable comprises: assembling together the tape cable, at least one contact having at least one tooth arranged to penetrate the insulating material on one side of the cable, a bolster on the other side of the cable, and a spring; pressing the assembly together to compress the spring; and inserting the compressed assembly endwise into a housing which is arranged to retain the assembly with the spring compressed.

Thus, the assembly (which may be considered as a multilayer sandwich consisting of the cable, contact, bolster and spring) may be pressed into the housing by a process similar to that of corking a bottle. Preferably, after the assembly has been inserted into the housing, the tape cable is drawn longitudinally across the tooth which ploughs through the insulating material to improve or to establish electrical contact with a metallic tape. After the tape has been drawn longitudinally the tape may be clamped to the housing so as to transfer loads between the cable and the housing, thus relieving the portion of the cable in contact with the teeth of such loads. A very satisfactory way of clamping the tape is by crimping a portion of the housing on to the tape.

The method of assembly makes it possible to employ a simple one-piece housing which may be generally tubular and preferably has a flared mouth to assist the insertion of the assembly into the housing. Preferably also the housing has inwardly directed means such as dimples, barbs or setscrews for retaining the assembly in the housing.

The invention may be carried into practice in various ways but one connector and its method of attachment to a tape cable in accordance with the invention will now be described by way of example with reference to the accompanying drawings, in which:

FIG. 1 is a plan view of the connector attached to the tape cable;

FIG. 2 is a section on the line II-II of FIG. 1 showing the attached connector;

FIG. 3 shows the components of the connector prior to attachment to the tape cable; and

FIGS. 4, 5 and 6 show successive stages in the process of attachment.

Reference will first be made to FIGS. 1 and 2. The connector has a one-piece metal housing 1 which is approximately rectangular in cross section perpendicular to the plane of section of FIG. 2 and has a flared portion 2 leading away from an open mouth 3, a portion 4 of constant cross section behind the flared portion, a portion 5 of reducing cross section, and a flared portion 6. The connector is attached to a tape cable 7, which comprises 14 metal tapes 8 which are embedded side-by-side in a plastics insulating material. Contact with the tapes is made by 19 contact members 10 each of which is made from a bar of brass and has flanges 11 and 12 on one side at the ends to retain the bar longitudinally in a groove in a common insulating contact carrier 13. On the opposite side from the flanges, the bar has two chisel-shaped teeth 15 having sharp leading edges 15a with relieved surfaces 15b behind them. The connector also includes a bolster in the form of a resilient pad

16 and, on the other side of the contact carrier 13, a rectangular convoluted plate spring 17 which has a constant cross section (shown in FIG. 2) and extends across the entire width of the contact carrier.

5 The connector is attached to the tape cable in the following way. As shown in FIG. 3, the end of the tape cable 7 is passed right through the housing 1 so that it extends some distance beyond the housing. The pad 16 is placed underneath the tape cable and the contact carrier 13 with the contacts 10 is placed on top of the cable. The spring is placed on top of the contact carrier 13. This four-layer sandwich is then placed between the jaws 18 of a tool which is not shown in the drawings. The jaws are then moved together to compress the sandwich. The flared mouth 3 of the housing is then moved against the jaws 18 on one side and a pusher element 19 is moved against the sandwich on the other side. Movement of the pusher element is continued to push the sandwich through the flared mouth and into the section 4 of the housing where the sandwich is 10 retained — primarily by friction produced by the expanding force of the spring 17 and the pad 16, but also by means of barbs 20 formed by inwardly directed tongues stamped from the sides of the housing. The jaws 21 of another tool then grip the tool cable and, while the housing is held stationary, the jaws 21 draw the cable across the teeth to the right (as viewed in FIG. 5) and this causes the teeth to plough into the insulation of the tape cable and make reliable electric contact with the metal tapes along the full length of the relieved surfaces 15b of the teeth. The tape cable is then anchored to the rear part of the housing behind the compressed sandwich by crimping the rear part of the housing on to the tape cable by means of crimping jaws 22. This completes the process, as shown in FIG. 6, and the jaws 21 and 22 may be opened to release the connector.

25 The tools for carrying out the various processes described may take different forms. For example, the jaws 18 may be afforded by a hand tool similar to hand crimpers and having means for limiting the approach of the two jaws towards one another. The other jaws may also be afforded by simple hand tools. On the other hand it will be apparent that one or more simple powered tools can be devised for carrying out the several stages of the process.

30 What I claim as my invention and desire to secure by Letters Patent is:

- 45 1. A method of attaching a tape cable connector to a tape cable consisting of at least one metallic tape embedded in insulating material, the method comprising:
- 50 forming a multilayer assembly by superimposing on one another layers comprising said tape cable, at least one electrical contact having at least one tooth arranged to penetrate the insulating material on one side of said cable, a bolster on the other side of said cable, and a spring; pressing said multilayer assembly together to compress the spring; and
- 55 inserting the compressed multilayer assembly endwise into a tubular one-piece housing so that the longitudinal axis of the layers is aligned with the longitudinal axis of the housing and whereby the assembly is retained in said housing with said spring compressed.
- 60 2. A method according to claim 1 wherein said bolster is resilient and said spring is positioned on the opposite side of said contact from said cable.
- 65 3. A method according to claim 1 wherein, after said multilayer assembly has been inserted into said housing, said tape cable is drawn longitudinally across said tooth whereby said tooth is caused to plow through the insulating material on said one side of said cable.
- 70 4. A method according to claim 3 wherein, after said step of drawing said tape longitudinally, said tape is clamped to said housing.
- 75 5. A method according to claim 4 wherein said tape is clamped to said housing by crimping a portion of said housing onto said tape.

6. A combination of a tape cable consisting of at least one metallic tape embedded in insulating material and a tape cable connector attached thereto, said connector comprising:

a generally one-piece tubular housing into one end of which said tape cable extends;

a multilayer assembly which comprises superimposed on one another layers comprising at least one electrical contact having at least one tooth extending through the insulating material on one side of said cable into electrical contact with said metallic tape, a bolster on the opposite side of said cable, and a spring;

said multilayer assembly being located between opposite inwardly facing wall surfaces of said housing with the longitudinal axis of the layers aligned with the longitudinal axis of the housing; and

said walls being spaced apart by such a distance that said spring is compressed whereby to press said tooth against said metallic tape.

7. A combination according to claim 6 wherein said housing has a flared mouth to receive said compressed assembly. 20

8. A combination according to claim 6 wherein said housing has inwardly directed means to retain said assembly therein.

9. A combination of a tape cable consisting of at least one metallic tape embedded in insulating material and a tape cable connector attached thereto, said connector comprising:

a one-piece generally tubular housing into one end of which said tape cable extends;

a multilayer assembly which comprises superimposed on one another layers comprising at least one electrical contact having at least one tooth extending through the insulating material on one side of said tape cable into electrical contact with said metallic tape, a bolster on the opposite side of said cable, and a spring;

said multilayer assembly being located between opposite inwardly facing wall surfaces of the housing with the longitudinal axis of the layers aligned with the longitudinal axis of the housing;

said assembly being retained within the housing by inwardly directed barbs on the housing;

said walls being spaced apart by such a distance that said spring is compressed whereby to press the said tooth against said metallic tape.
